W. P. MURPHY.
CAR ROOF.
APPLICATION FILED APR. 26, 1920.

1,418,959.

Patented June 6, 1922.

UNITED STATES PATENT OFFICE.

WALTER P. MURPHY, OF NEW YORK, N. Y., ASSIGNOR TO P. H. MURPHY COMPANY, OF PARNASSUS, PENNSYLVANIA, A CORPORATION OF PENNSYLVANIA.

CAR ROOF.

1,418,959.

Specification of Letters Patent. Patented June 6, 1922.

Application filed April 26, 1920. Serial No. 376,612.

To all whom it may concern:

Be it known that I, WALTER P. MURPHY, a citizen of the United States, and a resident of the city of New York, in the county of 5 New York and State of New York, have invented a new and useful Improvement in Car Roofs, of which the following is a specification.

This invention relates principally to car 10 roofs of the corrugated radial type shown in my Patent No. 1,227,484, dated May 22, 1917 wherein corrugated roof sheets extend entirely across the car and are secured at their lapped side margins to the car sub- 15 structure at the eaves and ridge portions thereof.

One of the principal objects of the present invention is to provide a simple and efficient means for securing the eaves portions of 20 the sheets to the car substructure, to provide for ventilation at the eaves, to provide a weather-proof eaves construction and to facilitate the attachment of the roof parts to the car. The invention consists principally 25 in means for securing the eaves ends of the sheets to the car, and it further consists in the construction and combination of parts hereinafter described and claimed.

In the accompanying drawing, which 30 forms part of this specification, wherein like symbols refer to like parts wherever they occur,—

Fig. 1 is a plan view of the eaves portion of a car roof embodying my invention, parts 35 broken away to more clearly illustrate the invention;

Fig. 2 is a side elevation of the eaves portion of the car shown in Fig. 1 with parts broken away to disclose the ends of the 40 sheets and the eaves ends;

Fig. 3 is an enlarged vertical cross section through the eaves portion of the roof on the line 3—3 in Fig. 2;

Fig. 4 is a cross section similar to Fig. 45 3, the section being taken through one of the securing bolts on the line 4—4 in Fig. 2;

Fig. 5 is a fragmentary side view of the 50 eaves portion of the roof in the region of a securing bolt; and

Fig. 6 is a view similar to Fig. 3 showing a modified form of eaves construction.

The present roof comprises rigid load sustaining corrugated metal roof sheets 7 arched transversely of the car and extending 55 from side plate to side plate with their cor-

rugations extending cross-wise of the car. The side margins of each sheet overlap the side margins of the adjacent sheet, the corrugations of the respective sheets engaging each other to form seams or joints, the extent of the overlap being preferably two or three corrugations. The eaves ends of the roof sheets are supported on the outwardly extending upper flange of an angle iron eaves strip 8. The eaves strip is arranged 60 longitudinally of the car side with its vertical flange extending down parallel with the outer surface of the side sheathing 9. The eaves angle is secured to the outer face of the side sheathing along the upper surface thereof with carriage bolts 10 that extend horizontally through the side sheathing 9 and the side plate 11. The bolts 10 are provided with nuts on their inner ends, which bear against the inner face of the side plate and hold said bolts in place. 70

Extending lengthwise of the car, at the eaves thereof, is a combined eaves cap and facia 12 of angular section which serves as a flashing and retaining member for the eaves 80 ends of the sheets. The upper flange of the eaves cap extends inwardly parallel with the pitch of the roof and overlies the eaves marginal portion of the sheets. The other flange of the eaves strip extends downwardly across the openings formed between the top flange of the eaves angle and the crest of the corrugations to prevent rain and snow from blowing through these openings and entering the interior of the car. The depending flange of the eaves cap is spaced laterally from the ends of the sheet far enough to form a space to permit air to enter the openings formed by the corrugations for 85 ventilating purposes and to permit rain, snow and cinders to pass off the eaves of the roof. The eaves cap extends across the entire width of the eaves ends of the sheets, thereby firmly holding the sheets down at the eaves, and the eaves cap, together with 90 the eaves portions of the lapped side margins of the roof sheets, are firmly secured to the eaves angle 8 by means of bolts 13. These bolts pass through the lapped side margins of the sheets, as well as the eaves cap, and prevent the sheets from pulling out from beneath the top flange of the eaves cap. 95

The depending flange of the eaves cap is punched out at intervals, forming tongues 110

14, which are inclined inwardly and downwardly from the depending flange with their free lower ends engaging the upper surface of the eaves angle. These tongues act as 5 spacers and prevent the eaves cap from crushing the ends of the sheets when the nuts of the bolts 13 are drawn tight. These 10 tongues also stiffen the eaves cap and prevent sagging of the same and also transmit the pressure caused by tightening the nuts 15 of the securing bolts directly to the eaves angle, thus relieving the eaves ends of the sheets of this pressure as well as the weight of the eaves cap. The eaves cap may be 20 equipped with two sets of tongues, one adapted to bear on the eaves angle, as shown in Fig. 3, and the other on the sheet, as shown in Fig. 6. The tongues 14^a which engage the sheets, bear upon the upper surfaces 25 of the valleys of their corrugations, thereby firmly clamping the sheets to the horizontal flange of the eaves angle and also permitting the tongues to act as spacers for holding the upper flange of the eaves cap a pre-determined distance from the eaves angle. In Fig. 6, a slightly modified form of eaves angle 8^a is shown, the upper flange of the eaves angle being disposed horizontally instead of being inclined to conform to the 30 pitch of the roof, as shown in Fig. 3, and the securing bolt 13^a being shown with its head portion uppermost.

The eaves cap may be provided with any 35 desired number of tongues. For instance, it may be desirable to provide a tongue for every other corrugation, or, if desired, all of the tongues can be made to bear against either the eaves angle or the sheets.

What I claim is:

40 1. A car roof comprising roof sheets arranged crosswise of the car and eaves caps secured to the car and covering the eaves ends of said roof sheets, said eaves caps having portions which bear against the 45 car substructure and space the same therefrom, and having integral tongue portions which bear against the roof sheets and hold the same down on the car substructure.

2. A car roof comprising roof sheets extending crosswise of the car and connected 50 along their side margins by joints, a continuous eaves cap covering the eaves ends of said roof sheets, and vertically disposed fasteners securing said cap to the car, said eaves 55 cap extending above the tops of the joints and having a plurality of integral tongue portions which engage the sheets between joints.

3. A car roof comprising roof sheets extending crosswise of the car and supported 60 at their eaves ends on the car substructure, said roof sheets having raised ribs and their adjacent side margins overlapped to form joints, and an eaves cap extending lengthwise of the car and covering the eaves ends

of said roof sheets, said eaves cap being secured to the car substructure and having portions extending into the raised ribs of said sheets, said portions being adapted to bear against the car substructure to space 70 said eaves cap a desired distance above the car substructure.

4. A car roof comprising roof sheets extending crosswise of the car and connected along their side margins and an eaves cap 75 secured to the car lengthwise of the same along the eaves thereof and means for securing said cap to the car, said eaves cap being of angle section and having one flange overlying the eaves ends of the sheets and 80 having the other flange extending opposite the ends thereof, said eaves cap having tongue portions which engage the car substructure and take the pressure of the securing means and thereby relieve the roof 85 sheets from such pressure.

5. A car roof comprising roof sheets arranged crosswise of the car and an eaves cap secured to the car and covering the eaves ends of said sheets and vertically disposed fasteners for said cap, said eaves cap having mean integral therewith which bear vertically against the car substructure and space said eaves cap a desired distance above the car substructure. 95

6. A car roof comprising metal roof sheets extending crosswise of the car, and an angle shaped eaves cap secured to the car substructure and covering the eaves ends of said sheets, said eaves cap having one of its 100 flanges above the sheets and the other extending downwardly across the ends thereof, the downwardly extending flange of said eaves cap having inwardly extending tongue portions struck therefrom and 105 adapted to engage the car substructure to space the eaves cap therefrom.

7. A car roof comprising corrugated metal roof sheets extending crosswise of the car and lapped at their side margins, and an angle shaped eaves cap secured to the car substructure and covering the eaves ends of 110 said sheets, said eaves cap having one of its flanges above the sheets and the other extending downwardly across the ends thereof and spaced laterally therefrom, the downwardly extending flange of said eaves cap having inwardly extending tongue portions struck therefrom and adapted to extend into the corrugations of the sheets and engage the car substructure to space the eaves cap therefrom. 115 120

8. A car roof comprising corrugated metal roof sheets extending crosswise of the car and lapped along their side margins, an angle eaves cap for flashing and holding down the eaves ends of said sheets and fastening device extending through said sheets and said eaves cap, said eaves cap having one of its flanges above said sheets 125 130

- and its other flange extending downwardly across the ends of said sheets, the downwardly extending flange of said eaves cap having tongue portions struck therefrom adapted to engage the car substruction for spacing the inwardly extending flange of said eaves cap a desired distance above said roof sheets.
9. A car roof comprising corrugated metal roof sheets extending crosswise of the car and lapped along their side margins, an angle eaves cap for flashing and holding down the eaves ends of said sheets and fastening device extending through the lapped side margins of said sheets and said eaves cap for securing said sheets and said eaves cap, said eaves cap having one of its flanges extending inwardly over the eaves ends of said sheets and its other flange extending downwardly across the ends of said sheets and spaced laterally therefrom, the downwardly extending flange of said eaves cap having tongue portions struck there-
- from adapted to enter some of the corrugations of said sheets and to engage the car 25 substructure for spacing the inwardly extending flange of said eaves cap a desired distance above said roof sheets.
10. A car roof comprising side plates and corrugated metal roof sheets arranged crosswise of the car, eaves strips secured to said side plates for supporting the eaves ends of said roof sheets, eaves caps of angle section covering the eaves ends of said roof sheets, fastening means extending through 30 said eaves caps and said roof sheets for securing said members to said eaves strips, said eaves caps having projecting portions integral therewith adapted to enter the ends of some of the corrugations of said sheets 35 and to engage said eaves strip for spacing said eaves caps a desired distance therefrom.

Signed at Chicago, Ill., this 14th day of April, 1920.

WALTER P. MURPHY.
